SELF-INDUCTANCE

Mendel Osnos, Berlin, Germany, assignor to Telefunken Gesellschaft für Drahtlose Telegraphie m. b. H., Berlin, Germany, a corporation of Germany

Application October 28, 1933, Serial No. 695,564
In Germany November 2, 1932

5 Claims. (Cl. 175—359)

The present invention relates broadly to inductance coils and more specifically to inductance coils with variable or controllable temperature dependency.

5 In copending U. S. application Serial No. 683,240 certain embodiments of self-inductances are shown by way of example as springy spirals which are arranged to press against a surrounding cylinder preferably of quartz. In the system described in said application, if the cylinder is to be composed of quartz or the like it is very difficult to make the inner surface entirely cylindrical. Hence it is difficult to accomplish a complete pressing of the self-induction coils against the quartz cylinder.

10 15 In order to avoid these drawbacks the present invention proposes to arrange between the quartz cylinder and the self-induction coil a suitably split cylinder of a material that will easily afford obtaining an accurately cylindrical inner form. It has been found that materials such as hard rubber or the like give excellent results.

20 25 In the accompanying drawing three embodiments of the invention are shown by way of example.

Figure 1 is a partial cross sectional view of a form of the invention wherein the inductance coil is made of elastic material;

Figure 2 shows a partial sectional view of an arrangement made up in accordance with the invention wherein the pressing force is obtained by an additional spring device; and,

Figure 3 is a partial cross sectional view of an embodiment of the invention wherein only one split cylinder is utilized.

30 35 In Figure 1 a quartz cylinder 1 has inserted in it a split cylinder 3 and the inductance coil 2. In this particular embodiment the coil 2 is suitably constructed so as to force the split cylinder 3 up against the quartz cylinder 1. In this way the coil is maintained at a practically uniform diameter. The split cylinder 3 is preferably constructed of an insulating material.

40 45 Figure 2 indicates the application of the inventive idea to an unelastic induction coil. Herein are 1, 2 and 3 the same elements as those in Figure 1 excepting 2 to be simply used as spring and not also as an inductance, 4 is the rigid induction coil. In this case cylinder 3 is 50 doubly used at the inside as well as outside of coil 4.

55 The use of the outer cylinder 3 composed of hard rubber or material highly expanding under heat, give the advantage that the outer diameter of the induction coil is not only prevented from

increasing but may actually decrease with increase in temperature.

In said U. S. patent application Serial No. 683,240 the embodiments of self-inductances are shown by way of example as being composed of 5 springy spirals which due to their construction press against the surrounding cylinder. They are of practical usefulness as long as they represent small self-inductances. Larger self-inductances however, are made of soft wire or litz wire, thus not having an inherent springy force to cause them to be pressed against the cylinder.

10 15 A feature of the present invention comprises winding the self-inductances upon a cylinder split in the longitudinal direction into two or more portions or they are wound upon several cylinder parts and these only are pressed by means of a spring force or spiral spring respectively, against the cylinder surrounding the winding.

20 25 In Figure 3, numeral 1 is a cylinder limiting the diameter of the induction coil and which is composed of quartz for instance, 2 designates the springy spiral suitably of copper, 3 is a cylinder of insulating material (such as pressboard, hard rubber or the like) split into two or several portions, and 4 represents an induction winding wound upon a cylinder and consisting for instance of copper strand wire. The springy spiral 2 presses the two cylinder halves and thus also 30 35 the winding itself against the cylinder 1 intended to limit the diameter of the winding.

In order to avoid losses the helix 2 will preferably be made of copper wire. In this case the helix 2 can also be used as additional self-inductance. It is preferable to make the split between the cylinder halves or the splits between the single cylinder parts as narrow as possible.

40 I claim:

1. In an inductance coil assembly a quartz cylinder, a split sleeve made up of insulation material within said cylinder and a metallic spiral coil within the split sleeve said coil being arranged so as to firmly retain the split sleeve 45 within the cylinder.

2. An inductance coil comprising a quartz cylinder, a metallic spiral inductance coil engaging the internal wall of said quartz cylinder and a split sleeve arrangement made of insulation material within said spiral and means comprising a metallic spiral coil engaging the internal wall of the split sleeve so as to firmly retain said first named coil within said cylinder.

50 55 3. An inductance coil comprising a quartz

cylinder, a split sleeve within said cylinder, a metallic spiral inductance engaging the internal wall of said split sleeve, a second split sleeve within said spiral inductance coil and a metallic spiral coil engaging the internal wall of the second named split sleeve so as to firmly retain said two split sleeves and inductance coil within said cylinder.

4. A system as described in the next preceding
10 claim further characterized by that the two split sleeves are made of an insulation material.

5. An inductance coil assembly comprising a cylinder made of a material having an extremely low coefficient of expansion with changes in temperature, a split sleeve within said cylinder and a metallic spiral coil within the split sleeve said coil being arranged so as to firmly retain itself against the split sleeve while at the same time retaining the split sleeve within the cylinder.

MENDEL OSNOS.
